MACHINE FOR PREPARING WOOD BLOCKS
FOR KILN DRYINGJesse O. Matteson, Muskegon, Mich., assignor to
The Brunswick-Balke-Collender Company, Chi-
cago, Ill., a corporation of Delaware

Application December 24, 1938, Serial No. 247,562

5 Claims. (Cl. 91—51)

This invention relates to an improved machine for preparing wood blocks for kiln drying and has for one of its principal objects the ready and convenient application of a resinous or other paint coating to a block of wood so as to protect the same from undesirable splitting and checking while in the process of drying in a kiln.

This particular invention has to do with the preparation of a wood block such as that described in United States Letters Patent to McKenzie, No. 2,120,368, dated June 14, 1938.

An important object of this invention resides in the production of a machine wherein wooden blocks, particularly blocks or billets of wood such as those used in the production of bowling pins, can be readily and quickly covered on their heart and bark faces with a protective coating of some resinous paint or the like and wherein much of the hand labor in performing this operation is eliminated.

Still another important object of the invention resides in the production of a machine for coating wood blocks or the like preparatory to their being dried in a kiln, whereby certain portions of the block may be simply, adequately and efficiently coated or covered with a protective layer of paint or the like and wherein this operation can be also performed much more accurately than is ordinarily possible by hand.

Other and further important objects of the invention will be apparent from the disclosures in the accompanying drawings and following specification.

The invention, in a preferred form, is illustrated in the drawings and hereinafter more fully described.

In the drawings—

Figure 1 is a side elevation of the improved coating machine of this invention showing certain essential details and also showing the method of handling the wooden blocks in passing the same through the machine;

Figure 2 is a view of the motor, a portion of the tank, and the wheel or drum by means of which the resinous coating is applied to the billets or blocks of wood in proper amount;

Figure 3 is a detail view of a block of wood coated in the machine of this invention;

Figure 4 is a diagrammatic view showing the wiring by means of which the contents of the coating tank are kept at the proper temperature and viscosity; and

Figure 5 is an enlarged sectional view of the face of the coating drum or wheel.

As shown in the drawings—

The reference numeral 10 indicates generally the tank in which the resinous paint or other coating material of this invention is kept. Mounted in this tank for rotation therein is a drum 12 positioned on a shaft 14, driven by a motor 16 and speed reducer 18.

A temperature control for the contents of the tank 10 is indicated at 20; a starting box at 22; and a starting switch at 24. This keeps the coating at desired viscosity.

A conveyor 26 leads from a preliminary storage or conditioning room to the apparatus of this invention, and another conveyor 28 is mounted at the other end of the machine for the purpose of carrying the coated or "doped" pins 15 to trucks or the like whereon they are delivered to the drying kilns.

The drum 12 is composed of a main body portion including a metallic rim, this being covered with a cushion comprising a layer of steel wool pads or the like, as illustrated at 30, this steel wool in turn being covered with a layer of canvas or a fine metal screen, as shown at 32, the whole being held in position by means of plies of baling wire or the like 34 wound around the 25 drum. Wire mesh or glass cloth may also be used.

The resistance elements 40 by means of which the temperature in the tank 10 is controlled, are connected to a source of electrical energy 42 through the thermostat 20, and a block or billet of wood which is adapted to be treated in this machine is illustrated at 44 in Figure 1. The block 44, with a coating 46 thereon, showing the same after it has passed through the machine, is 35 illustrated in Figure 3.

In operation the block to be treated is first held manually in the position shown in the full lines 44 in Figure 1 and allowed to pass over the wheel with either its heart or its bark face contacting the wheel or drum 12, and inasmuch as the wheel or drum 12 is dipping into the melted resinous paint or other material in the tank 10, this face of the block or billet is immediately covered with the composition to a width approximating the effective operating width of the wheel or drum 12, as shown by the band 46 in Figure 3. The pin block is then turned by the operator to the position shown at 48 in Figure 1, whereupon one end of the block is accordingly coated. After 50 this has been accomplished the pin is then turned to the position shown at 50 in Figure 1 and again advanced horizontally toward the left in that figure; after which it is finally turned to the position shown in 52 which covers the other end 55

of the block, thereby accomplishing a complete desired coating of the ends and of the heart and bark faces, which accordingly acts to prevent undue checking or splitting, all as described in the aforesaid McKenzie patent.

I am aware that many changes may be made and numerous details of construction varied throughout a wide range without departing from the principles of this invention, and I therefore do not propose limiting the patent granted thereon otherwise than as necessitated by the prior art.

I claim as my invention—

1. A machine for coating wood blocks preparatory to kiln drying comprising a container for the coating material, a drum rotatably mounted in the container, with its upper portion above the upper edge of the container, means for continuously rotating the drum at a relatively slow speed, and cushion means on the drum for applying a layer of coating material to a block of wood when the same is held against the drum, comprising a resilient and porous stuffing of non-absorbent material and an outer foraminous covering.

2. A machine for coating wood blocks preparatory to kiln drying comprising a container for the coating material, a drum rotatably mounted in the container, with its upper portion above the upper edge of the container, means for continuously rotating the drum at a relatively slow speed, and cushion means on the drum for applying a layer of coating material to a block of wood when the same is held against the drum, said cushion means including a layer of steel wool on the surface of the drum.

3. A machine for coating wood blocks preparatory to kiln drying comprising a container for the

coating material, a drum rotatably mounted in the container, with its upper portion above the upper edge of the container, means for continuously rotating the drum at a relatively slow speed, and cushion means on the drum for applying a layer of coating material to a block of wood when the same is held against the drum, said cushion means comprising layers of steel wool and canvas on the surface of the drum.

4. A machine for coating wood blocks preparatory to kiln drying comprising a container for the coating material, a drum rotatably mounted in the container, with its upper portion above the upper edge of the container, means for continuously rotating the drum at a relatively slow speed, and cushion means on the drum for applying a layer of coating material to a block of wood when the same is held against the drum, said cushion means comprising a resilient and porous layer of non-absorbent material and a wire mesh covering on the surface of the drum, and means for retaining said cushion means on the drum face.

5. A machine for coating wood blocks preparatory to kiln drying comprising a container for the coating material, a drum rotatably mounted in the container, with its upper portion above the upper edge of the container, means for continuously rotating the drum at a relatively slow speed, and cushion means on the drum for applying a layer of coating material to a block of wood when the same is held against the drum, said cushion means comprising layers of woven glass fibers on the surface of the drum, and means for retaining said absorbent cushion layers on the drum face, said means comprising wire hoops.

JESSE O. MATTESON.
